 Bloomer Bros. Company, Newark, N. Y., a
 corporation of New York

Application October 21, 1931. Serial No. 570,066

7 Claims. (Cl. 229—29)

This invention relates to containers of the class having integral transverse partition members arranged to retain fragile articles, such for example as eggs, and pertains more particularly to a new and improved longitudinal partition member for such containers.

One object of the invention is the provision of such a longitudinal member having an improved, simple, and satisfactory cushioning member which will protect the eggs against breakage.

Another object of the invention is the provision of such a longitudinal member which both locks the transverse members in erected position and resiliently supports the fragile articles, such for example as eggs.

A further object is the provision of a longitudinal member of this kind which provides separate independent resilient bottoms for each of the article receiving compartments.

To these and other ends the invention resides in certain improvements and combinations of parts, all as will be hereinafter more fully described, the novel features being pointed out in the claims at the end of the specification.

In the drawing:

Fig. 1 is a plan view of a container constructed in accordance with the preferred embodiment of the invention, the cover being shown in open position and partly broken away;

Fig. 2 is a fragmentary vertical sectional view taken substantially along the center line of the container illustrated in Fig. 1, the cover being shown in closed position;

Fig. 3 is a vertical sectional view taken transversely of the container illustrated in Fig. 1, showing the cover in closed position;

Fig. 4 is a view similar to Fig. 3 with the longitudinal partition member removed and with the cover in open position and partly broken away;

Fig. 5 is an enlarged fragmentary plan view of the container illustrated in Fig. 1, with the cushioning member removed and showing the transverse partition members or flaps in the elevated position;

Fig. 6 is a plan view of the preferred form of the central longitudinal partition member in the open or flat position before being applied to the container, and

Fig. 7 is a fragmentary view of the cover locking strip showing the relation of the locking lugs thereto.

Similar reference numerals throughout the several views indicate the same parts.

Referring to the drawing there is shown a container formed to provide a bottom 11, back 12,

front 13, and a cover 14 having an integral locking flap 15. The front 13 is lower than the back 12 and has formed integral therewith a false top which extends the full width of the container, and which is provided along its free longitudinal edge with an attaching strip 20 which is bent upwardly and adhesively or otherwise permanently secured to the back 12, as clearly shown in Figs. 3 and 4. The false top has formed therefrom, in a manner to be presently described, a 65 plurality of transverse partition members 21 which extend substantially the full width of the top, and which are connected to the front 13 and strip 20 by means of integral triangular corner pieces 22. All of the parts are preferably made from a 70 single sheet of cardboard, or other similar material, suitably scored, folded, and pasted to form the structure illustrated in Fig. 4.

The transverse partitions 21 are formed by slitting the false top (see Fig. 5) along the lines 25, 75 26, and 27, and scoring along the lines 28 which form one edge of the corner pieces 22. The score lines 28 constitute hinged connections between the corner pieces 22 and the partitions 21, and enable the latter to be swung down at right angles to 80 the top, as illustrated in Fig. 4. The corner pieces 22 thus not only secure the transverse partition members 21 to the front 13 and strip 20, but those adjacent the front 13 cooperate with the locking flap 15 to lock the cover 14 in closed position. 85 To enable these front corner pieces to lock the cover, the flap 15 is provided with a plurality of L-shaped notches 30, the edges of which are beveled as shown at 31, Fig. 7. When the cover 14 is closed, the flap 15 is engaged with the inner face 90 of the front 13 and the notches 30 engage the corner pieces 22 to lock the cover in closed position, in the manner well known in the art.

Each of the transverse members 21 is provided with a vertically disposed slot or notch 35 extending 95 downwardly from the upper edge thereof, as illustrated in Fig. 4, and adapted to receive a central longitudinal partition member generally indicated by the numeral 40 (Fig. 6). This longitudinal member is preferably in the form of a 100 single sheet of cardboard, or similar material, folded upon itself along the central line 41 to form two superimposed upstanding panels 42 and 43 symmetrically disposed with relation to the longitudinal center line of the container and forming a central longitudinal partition which divides the compartments formed by the transverse members into a plurality of article receiving cells 44, each of which is adapted to receive a single article, such as an egg. The panels are provided 110

with a plurality of slots 45 which extend upwardly from the lower edges thereof, substantially in the planes of the members 21, and terminate at or slightly above the bottoms of the notches 35, so that the panels will either normally rest on and be supported by the bottoms of the notches, or will actually rest thereon when subjected to a slight downward pressure. These slots subdivide the lower portions of the panels 42 and 43 into a plurality of tabs or tongues 46, each of which is of such a width as to fit readily between two adjacent transverse members 21, thus securely locking these members against oscillation. The member 40 is also provided with end tabs 47 of a width less than the tabs 46 and cooperating therewith to retain the end transverse members in vertical position.

In containers of the class above described, it is desirable to provide means for resiliently supporting the articles within the container. It has been found that the tabs 46 are admirably adapted to provide such supports. To this end the panels 42 and 43 are lightly scored along the parallel lines 50, see Fig. 6, and the tabs 46 are extended obliquely outwardly and downwardly to rest on the bottom 11 adjacent the back 12 and the front 13, as clearly illustrated in Fig. 3. These tabs thus extend laterally under the cells 44 and provide separate independent bottoms therefor. While the outer free edges of the tabs are supported by the bottom, the inner edges are held in elevated position by the panels 42 and 43, which are in turn supported by the transverse members 21. The tabs thus provide inclined bottoms for the cells which resiliently support the eggs and protect them against breakage. Although the panels 42 and 43 and the tabs 46 have been shown as being made from a single piece of material, it is evident that they may be divided along the line 41 to form two separate members.

When the carton is to be filled it is opened in the usual manner and the transverse members are swung downwardly into vertical position, as shown in Fig. 4. The member 40 is then folded on the line 41 and is inserted in the slots 35 of the transverse members, the cushioning tabs 46 then being spread outwardly as shown in Fig. 3 to provide resilient bottoms for the cells 44. The articles are then placed in the cells and tend to depress the tabs 46 slightly. When, however, the cover is moved to closed position it engages the tops of the articles causing them to move downwardly and thus further bending or depressing the tabs 46, the amount of bending of the separate tabs being directly proportional to the size of the article supported thereon. When the tabs are thus depressed, the panels 42 and 43 will rest on the bottom of the notches 35, thus providing a support for the inner end of the tabs 46. By means of this arrangement the eggs are resiliently supported above the bottom 11 and are free to move downwardly when the cover is moved to closed position, or when pressure is applied thereto, thus accordingly reducing the likelihood of breakage. This equalizing action of the separate tabs 46 also tends to give the eggs a more uniform appearance when the container is open for display.

It is evident upon inspection of Fig. 3 that when the cushioning tabs 46 are deflected, the free edges thereof tend to move outwardly. This outward thrust is resisted wholly by the back 12 and the front 13 of the container, so that these members may be considered broadly as abutment means for preventing outward movement of the

portions 46. It is also evident from Fig. 3 that the two opposite portions 46 form in effect an inverted V-shaped cushioning member, the central portion of which is folded upon itself to provide the upstanding panels 42 and 43 which constitute the central longitudinal partition member. While the back 12 and front 13 provide abutment means for the tabs 46, the bottom 11 and members 21 provide a support therefor.

From the foregoing description it is apparent that the cushioning members 46 not only afford separate resilient bottoms for the cells 44, but also provide means for securing and bracing the transverse members in vertical position. The panels 42 and 43, on the other hand, not only provide the central longitudinal partition member, but also constitute a stiffening rib which gives strength and rigidity to the entire container. By means of this arrangement the parts are held in proper assembled relation and the articles are effectively protected against breakage.

While the present embodiment has been described in connection with egg cartons, it is obvious that the same construction may be used in other types of containers. It is also obvious that the number of longitudinal partition members may be increased to provide a container having a greater number of rows of cells. The present invention is, therefore, not to be limited to the precise construction disclosed, but is intended to cover all variations and modifications thereof falling within the spirit of the invention or the scope of the appended claims.

I claim:

1. A container for fragile articles comprising a body having a bottom and front and rear corners, a partition member integral with and extending across said body, and a piece of flat sheet material folded upon itself to provide an upstanding partition portion extending substantially at right angles to said partition member and cushioning portions extending obliquely downwardly and outwardly toward said front and rear corners and having edges resting on said bottom to provide inclined cushioning bottoms for compartments formed by said partition member and partition portion.

2. A container for fragile articles comprising a body having a bottom and sides, a partition member extending across said body and having a slot therein, and a piece of sheet material having a slot therein and being folded upon itself to provide an upstanding partition portion extending at an angle to said partition member and being received at least partially in said slot in said partition member, said partition member being received at least partially in said slot in said sheet material, and said sheet material extending obliquely downwardly and outwardly to engage said bottom adjacent said sides to provide inclined cushioning bottoms for compartments formed by said partition member and partition portion.

3. A container for fragile articles comprising a body having a bottom and sides, a series of transverse partition members extending across said body and having slots in their upper edges, and a piece of sheet material folded upon itself and extending downwardly from the fold into said slots, said sheet material having portions extending outwardly and downwardly between said transverse partition members to provide cushioning bottoms for spaces between said transverse members, said outwardly and downwardly extending portions terminating in edges resting

on said bottom adjacent and substantially in engagement with said sides so that said sides hold said edges against outward movement.

4. A container for fragile articles comprising a body having a bottom, a series of transverse partition members extending across said body, a piece of sheet material extending longitudinally of said body to provide a longitudinal partition portion, and slots in said sheet material forming a series of tongues extending obliquely downwardly and away from said longitudinal partition portion, the outer ends of said tongues resting upon the bottom of said body to provide inclined cushioning bottoms for spaces between said partition members.

5. A container for fragile articles comprising a body having a bottom, a partition member formed integrally with the body and mounted for oscillation within said body about a substantially horizontal axis, and a cushioning element partially embracing said partition member to prevent oscillation thereof, said cushioning element being supported adjacent one end from said partition member, another end of said element resting upon and being supported by said bottom.

6. A container for fragile articles comprising a body having a bottom, means including transverse partition members extending across said

body for subdividing said body into a plurality of article receiving compartments, and means forming an obliquely inclined resilient cushioning bottom for each of said compartments, each of said cushioning bottoms when in use comprising a piece of sheet material resting upon said body bottom adjacent one side of its compartment and elevated above said body bottom and hung from said transverse partition members adjacent an opposite side of its said compartment, each cushioning bottom at its elevated side being curved upwardly and extending substantially vertically upwardly for a substantial distance.

7. A container for fragile articles comprising a body having a bottom, a series of cross partitions spaced from each other, a longitudinal partition interengaged with said cross partitions and supported by them, said longitudinal partition having an upstanding substantially vertical portion for subdividing space within said body into separate article-receiving compartments, and tongues extending from said longitudinal partition at a point above said bottom obliquely downwardly to said bottom and resting thereon to provide inclined cushioning supports for articles placed in the spaces between said cross partition.
